BY

Milton S. Grandell,
ATTORNEY

UNITED STATES PATENT OFFICE.

HERMAN HINMAN LUEDER, OF SIOUX CITY, IOWA.

FLOOR WAXING AND POLISHING MACHINE.

1,202,862.

Specification of Letters Patent. Patented Oct. 31, 1916.

Application filed April 10, 1916. Serial No. 90,054.

To all whom it may concern:

Be it known that I, HERMAN H. LUEDER, a citizen of the United States, and a resident of Sioux City, in the county of Woodbury 5 and State of Iowa, have invented certain new and useful Improvements in Floor Waxing and Polishing Machines, of which the following is a specification.

The present invention relates to means 10 for coating and polishing plane surfaces.

The invention has for its primary object the production of an improved device for waxing and polishing floors.

A further object of the invention is the 15 production of a device adapted to wax and polish floors more perfectly and rapidly, and with a minimum of labor.

Another object of the invention is the production in a device of this sort, of improved 20 means for regulating the amount of wax delivered, and for delivering the same uniformly.

A still further object of the invention is the production in a device of this sort of improved 25 means for regulating the wax-delivering means to suit the consistency of the wax.

Furthermore, the invention provides a 30 floor wlexer and polisher inexpensive in construction, effectively and easily operated, and readily adjustable.

With these and other objects in view, the invention, consisting in the construction, combination and novel arrangement of 35 parts, will be fully understood from the following description, reference being had to the accompanying drawings, which form a part of this application and in which like characters of reference indicate corresponding 40 parts throughout the several views, of which,—

Figure 1 is a side elevation of a device 45 constructed in accordance with the invention; Fig. 2 is a plan of the same; Fig. 3 is an enlarged transverse section of the wax-case; and Fig. 4 is an enlarged elevation of the wax-forcer adjustment.

Referring, now to the illustrations, the main frame of the embodiment chosen for 50 illustration, comprises horizontal side members, 5, provided at their rear ends with upwardly inclined handle-bars, 6. The in-

termediate portions of the side members are interconnected by cross-members, 7, upon which is mounted an electric motor, 8, or 55 other suitable rotary power. The main-frame is supported upon travel-wheels, 9, mounted on the side members, 5.

The motor-shaft, 10, carries a pulley, 11, connected by a belt, 12, with a pulley 13, 60 fixed on the spindle, 14, of a brush, 15, disposed between the front ends of the side members of the main-frame. The brush spindles are journaled in suitable bearings, 16, mounted on the main frame. 65

A vertically-movable frame is provided to support the wax-delivering means and comprises forwardly-extending arms, 17, pivoted on the motor-shaft, 10, and provided with rearwardly-inclined arms, 18, one of 70 which is extended and provided with a pawl 19, engageable with a quadrant, 20, mounted on the adjacent handle-bar, 6. The opposite arm, 17, of the movable frame, is bent laterally, as at 21, and firmly secured to the 75 companion arm to prevent relative movement between the two arms. Between the arms, 17, is mounted a suitable wax case, including side walls, 22, having lateral ears, 23, firmly secured to the arms, 17; and a 80 curved front and top wall, 24.

The case incloses a roller, 25, having spindles, 26, protruding through the side walls and journaled in bearings, 27, in the 85 ends of the movable frame arms, 17. The roller, 25, is rotated by a pulley, 28, mounted on one of the spindles, 26, and connected by a belt, 29, with the motor-pulley, 11. The wax within the case is forced against the roller, by means to be presently described, 90 and as the roller revolves in the wax and normally on the brush, it is obvious that a coat of wax will adhere to the roller and thus constantly wax the brush. The wax is forced downwardly and forwardly by a 95 concavo-convex plate, 30, the lower edge of which is pivoted as at 30^a, adjacent the lower rear corners of the side walls of the case.

The presser-plate is of sufficient width to pass freely between the side walls of the 100 case, and still prevent leakage of wax at the sides; and is pivoted concentric with the front wall in order that the presser plate may at all times be in contact therewith.

The presser-plate is held in yieldable engagement with the wax by a compression spring, 31, secured to the presser-plate, and carried by a bar, 32, the rear end of which is provided with notches, 33, engageable with a suitable stop, 34, carried by the movable frame member, 21.

The lower edge of the front wall of the case is formed with a flange, 35, the under 10 side of which is embraced by a strip, 36, secured to the flange by bolts, 37, which pass through the flange and transverse slots, 38, in the strip, whereby the strip may be adjusted toward or from the roller to regulate 15 the quantity of wax fed from the case. Between the lower edges of the side walls of the case, and at the rear of the roller, extends a cross-member, 39, which serves to reinforce the case and prevent leakage of 20 the wax at this point.

It is evident that in operation the roller delivers the wax uniformly upon the brush, and the latter applies it upon the surface being waxed, as the machine travels. The 25 compression on the presser-plate may also be varied at will by changing the adjustment of the slotted bar on the stop 34.

On the main-frame is secured a bracket, 41, having thereon an idler-pulley, 42, engaged by the lower lead of the belt, 29, to tighten the belt. By tilting the extended arm, 18 forwardly, and rearwardly, the belt 29, will be accordingly tightened or loosened. When sufficient wax has been distributed on 35 the floor, the arm 18 is tilted rearwardly, thereby raising the roller from the brush and slackening the belt, 29, to deenergize the waxing mechanism. The operation of the brush is then continued to polish the 40 floor.

Having thus described my invention, what I claim as new and desire to secure by Letters Patent, is,—

1. A surface waxer and polisher comprising 45 a suitable frame having a rotating drive member carried thereby and a rotatable surface waxer and polisher driven by said member, a second frame pivoted coaxially with said member, to move toward and from the 50 waxer and polisher, and a wax containing casing carried by the second frame and having a roller therein driven by said member and adapted to rest on the waxer and polisher, when the second frame is moved toward the waxer and polisher.

2. A surface waxing and polishing machine comprising a wheeled frame having a motor mounted thereon provided with a rotating drive member, a rotatable surface 60 waxer and polisher carried by the frame and driven by said member, a second frame pivoted coaxially with said member, a casing carried by the second frame and adapted to contain wax, a roller carried by the second 65 frame, inclosed by the casing, adapted to

rest on the waxer and polisher, and driven by said member, a plate adapted to yieldably force the wax toward the roller, and means for raising and lowering the second frame.

3. A surface waxing and polishing machine comprising a wheeled frame having a motor mounted thereon and provided with a rotating drive member, a surface waxing and polishing brush carried by the frame and driven by said member, a second frame, 70 movable in a vertical plane with respect to the wheeled frame, a wax-containing casing carried thereby and including side walls and a concavo-convex front and top wall, a roller rotatably carried by and between said side 75 walls, normally resting on the brush and driven by said member, means for moving the second frame vertically, and a yieldable plate pivoted between the side walls, concentric with the front and top wall and operating 80 to force the wax on the roller.

4. A surface waxing and polishing machine comprising a wheeled frame having a motor mounted thereon and provided with a rotating drive member, a surface waxing and polishing brush carried by the frame and driven by said member, a second frame pivoted coaxially with said member to swing in a vertical plane, a wax-containing casing carried by the second frame and including side walls and a concavo-convex front and top wall, a roller rotatably carried by and between the side walls, and normally resting on the said brush, a driving connection between the said roller and the driving member, and adapted to be placed in and out of operation, means controlled by upward and downward movement of the second frame for placing the driving connection out of and in operation, and a yieldable plate at 100 the rear of the casing to force the wax onto the brush.

5. A surface waxing and polishing machine comprising a wheeled frame having a motor mounted thereon and provided with a rotating drive member, a surface waxing and polishing brush carried by the frame and driven by said member, a second frame pivoted coaxially with said member to swing in a vertical plane, a wax containing casing carried by the second frame and including side walls and a concavo-convex front and top wall, a roller rotatably carried by and between the side walls, adapted to be coated with wax when rotated, normally resting on said brush to deliver the wax thereon, a driving connection between said roller and the driving member and adapted to be placed in and out of operation, means controlled by upward and downward movement of the second frame for placing the driving connection out of and in operation, a yieldable plate at the rear of the casing to force the wax onto said roller, and a cross member secured to the under side of the casing and ad- 110 115 120 125 130

justable toward and from the said roller to regulate the quantity of wax adhering thereto.

6. In a device of the class described, a surface waxer and wax-dispenser including a wax-containing casing having a concavo-convex wall and a plate pivoted concentric

therewith, and a roller within the casing adapted to deliver wax to the waxer, said plate being movable toward the roller to force the wax thereon.

In testimony whereof I have hereunto set my hand.

HERMAN HINMAN LUEDER.
